UNITED STATES PATENT OFFICE.

CHARLES EDWARD HAVILAND, OF LIMOGES, FRANCE.

DESIGN FOR A COVERED DISH.

SPECIFICATION forming part of Design No. 24,172, dated April 2, 1895.

Application filed December 13, 1894. Serial No. 531,732. Term of patent 7 years.

To all whom it may concern:

Be it known that I, CHARLES EDWARD HAVILAND, a citizen of the United States, residing at the city of Limoges, in the Republic of France, have invented and produced a new and original Design for a Covered Dish, of which the following is a specification, reference being had to the accompanying drawings, forming part thereof, in which—

10 Figure 1 is a top view of a covered dish bearing my design. Fig. 2 is a side elevation of same; and Fig. 3 is a detached sectional view through a portion of same on the dotted line 3—3 of Fig. 1.

15 The leading features of my design consist in the new and original shape and outline of the body of the dish and its cover and the ornamental scroll configurations thereon, as shown in the drawings forming a part of this 20 application.

In the drawings A designates the body of the dish and B the cover therefor, the said cover having a raised center bearing a handle C and ornamented by scrolls D, E, which form 25 an ornamental outline for that portion of the raised center of the cover which bears the said handle. The edge of the cover F is composed of the scalloped sections F along whose

edges are the ornamental scrolls G, as shown in Fig. 1. The sides of the body A are composed of the scalloped sections H which correspond and harmonize with the scalloped sections F of the cover B; and the said sides of the body A curve downward and outward and thence take a rather abrupt turn inward and 30 downward to the base I, as more clearly illustrated in Figs. 2 and 3. Upon the sides of the body A are the ornamental scrolls J which correspond in character with the scrolls G displayed upon the cover B. At opposite 35 ends of the body A are suitable handles K.

The form of the cover and body of the dish and the display of the ornamental scrolls thereon, the whole being as shown in the drawings, constitute an artistic, attractive 40 and distinctive design.

What I claim is—

The design for a covered dish; substantially as shown and described.

Signed at the city of Limoges, in the Republic of France, this 23d day of November, 50 A. D. 1894.

CHARLES EDWARD HAVILAND.
